UNITED STATES PATENT OFFICE.

RICHD. GORNALL, OF BALTIMORE, MARYLAND.

MACHINE FOR MAKING HOLLOW BULLETS.

Specification of Letters Patent No. 22,286, dated December 14, 1858.

To all whom it may concern:

Be it known that I, RICHARD GORNALL, of the city of Baltimore, in the State of Maryland, have invented a new and useful Machine for Making Hollow Bullets of the Minie or other Kind; and I do hereby declare that the following is a full, clear, and exact description of the same, reference being had to the accompanying drawings, 10 forming part of this specification, in which—

Figures 1 and 2 are opposite side views of the machine. Fig. 3, is a transverse vertical section in the plane indicated by the line x, x , in Fig. 1. Fig. 4, is a vertical section of the punch and dies which press the bullets, showing the form to which the bullet is brought by compression. Fig. 4*, is a plan, showing the arrangement of the finishing cutter relatively to the dies and core. 15 Figs. 5, 6 and 7, are views of some of the details of the machine. Figs. 8, and 9, are views of a bullet in its condition before and after the final operation of the machine.

Similar letter of reference indicate corresponding parts in the several figures.

My invention consists in the employment, in combination with a punch and set of dies for pressing the blanks or pieces of lead into a form approximating to that desired 30 for the bullets, of a revolving core which serves, firstly, to produce the cavities in the bullets, and secondly, as a mandrel to revolve the bullets for the purpose of finishing their exteriors by the operation of turning. My invention also consists in the employment of an automatically operating cutter in combination with the revolving core for the purpose of turning the bullets. 35 And it further consists in the employment in combination with the revolving core, of a female center having an automatic operation for the purpose of confining the bullets upon the revolving core during the turning operation and afterward releasing them and 40 moving out of the way to permit the succeeding operations of the dies.

To enable others to make and use my invention, I will proceed to describe its construction and operation.

50 A, is a table supported by standards B, B, and supporting two standards C, D, the whole combining to form a framing to carry the working parts of the machine. E, is the main shaft from which all parts of the machine derive motion, supported in bearings in the upper parts of the standards

C, D, and intended to have a constant rotary motion imparted to it by any suitable means.

F, is an upright cylindrical punch having a sharp lower edge and containing a conical cavity i , of a form corresponding with the desired form of the point and front portions of the bullets to be produced in the machine. The said punch operates in combination with a stationary die G, for the purpose of cutting circular blanks from a square bar of lead to be afterward formed into bullets by its action in combination with the pressing dies H, H, and core I. The die G, is secured within an arch formed in the lower 60 part of the standard C, and the punch F works in a guide in the said standard. The punch is secured to a cross head F', which is fitted to slide vertically upon two guide rods F², F², secured to the standard C, and 65 it derives motion from an eccentric wrist a , secured in a wrist plate or crank E¹, at one end of the driving shaft E, and working in a curved slot a^1 , in the cross head F¹.

b, b¹, are a pair of feed rollers for feeding the bar of lead over the die G, to be operated upon by the punch, said rollers working in bearings secured to one side of the standard C, and deriving motion at proper intervals to feed the bar from a wiper 80 or cam K, see Figs. 1 and 7, on the main shaft E, said wiper or cam acting upon the upper end of a lever K¹, which works on a fulcrum c¹, secured on one side of the standard C, and whose lower end carries a pawl 85 c, operating upon a ratchet wheel c², on the shaft of the upper roller b. The said lever K¹, is returned toward the shaft as the wiper K, recedes from it by means of a spring c³.

The pair of pressure dies H, are fitted to 90 slide horizontally in guides in the bottom of the standard C, close to the table A, said dies having semi-cylindrical cavities to fit the punch F. The core I, is arranged below 95 and in line with the punch F, and having its lower part of a size corresponding with the punch F, that it may fit closely within the dies H, H, when the latter are closed, and its upper part of a size and form to produce 100 the cavities in the bullets. The dies H, H, are opened and closed at suitable intervals of time by their connection by short links H¹, H¹, with the arms N¹, N¹, of two rock shafts N, N, which work in bearings d, d, 105 secured to the plate A, said rock-shafts being furnished with other arms N², N², which are connected by rods e, e, to, and derive motion 110

from, a vertical slide bar O, which is arranged in suitable guides attached to the standard C. This bar O, derives the necessary upward and downward movement to 5 operate the dies H, H, at the proper time from the forked end of a lever O¹, which is attached to the wrist a, before mentioned, and which contains a slot m, working on a stud f, secured in the punch cross-head F¹, 10 the forked end of the said lever being caused by the combined movements of the wrist and cross head to operate upon a projection g, on the face of the said bar O.

The punch, dies and core above described 15 operating in combination with each other, bring the bullet to the form shown in Fig. 8, also shown in the sectional view of the punch and dies in Fig. 4. The reason why the bullet is not finished to the form shown 20 in Fig. 9, by pressure, is, that the exterior surface of the punch and the surface of its interior cavity i, which constitutes a die would have to unite in a sharp edge which would not stand the operation of punching 25 out the blanks. By leaving the face of the punch thick enough to stand that operation, the shoulder n, is produced all around the bullet, and it is the cutting off this shoulder, as well as any fin that might be left at the 30 junction of the two dies H, H, that the turning operation is intended, principally, to effect, though I propose generally to turn nearly the entire exterior surface of the bullet to render it perfectly true and concentric to its interior cavity, and also to 35 turn the grooves v, v, for the cartridge twine.

To provide for its revolution to turn the bullets, the core I, is attached securely to, 40 or made in the same piece with a vertical shaft I¹, which is fitted to a suitable bearing in the plate A, but well supported vertically by a shoulder above the table; and to enable it to carry with it the bullets, I cut a slight 45 notch o, across the tip and down both sides (as shown in Figs. 3, 4, and 4*) into which a portion of the lead is forced by the pressing operation. The core is not intended to revolve during the pressing operation, but 50 its revolution is to commence as the dies open; and to provide for this the shaft I¹, is furnished with fast and loose pulleys h, h¹, to receive a band j, which runs in a groove in the fly-wheel L, on the main shaft E, and 55 which is shifted from one to the other of the said pulleys at the proper stage of the operation by means of a shipper lever P, which works on a stationary fulcrum k, below the table A, and which is operated by its connection by a link k¹, with the joint pin l, which connects the link H¹, of one of the dies H, to its respective arm N¹.

Q, is the cutter by which the exteriors of 60 the bullets are turned, having its edge formed like such portion of the intended

longitudinal profile of the exteriors of the bullets as it is intended to turn. This cutter, shown in Figs. 1, 2, 3, 4*, 5 and 6, is secured to the arm Q¹, of a vertical rockshaft R, which works in suitable bearings attached 70 to the standard C. This cutter is moved up toward the bullets as the dies open by the action of a cam S, on the main shaft E, on an arm R¹, on the upper part of the rockshaft and moved back to the position indicated in bold outline in Fig. 4*, out of the way of the dies H, H, and punch F, by means of a spring S¹, applied to the said arm R¹. The cam S, is so formed as to make the cutter advance quickly till it comes in contact with the bullet on the core and then very gradually, but to let it remain stationary for a limited period at the end of its advance that it may finish the bullet perfectly true. 80

p, is the movable female center which confines the bullets on the core during the turning operation, shown in Figs. 1, 2, 3, 4*, 5 and 6. This center, which is formed to fit the tip of the bullet, is attached to the horizontal arm s¹, of an upright bar T, which has an eye t, at each end, fitted loosely to the rockshaft R, and which is furnished with another arm s, which stands over the shaft E. This arm s, has a projection s², on one side, which occupies a position between the arm R¹, of the rockshaft R, and the shaft E, so that the spring S¹, acts through the arm R¹, upon the said projection to draw the female center to the position shown in bold outline in Fig. 4*, out of the way of the dies H, H, and punch F. The female center is moved to the position indicated in dotted outline in Fig. 4*, viz: directly over the center of the core I, after the rise of the punch F, and opening of the dies H, H, by the action of a cam U, made in the same piece with or arranged close to the cam S, and after it has moved to this position it is brought down on the bullet by the depressing action upon the bar T, of a spring w, coiled round the rockshaft R. The descent of the female center before it arrives over the center of the bullet is prevented by the action on the under side of the arm s, on the bar T, of the same cam K, which has been described as driving the feed rollers b, b¹. This cam K, when the proper time arrives, lifts the center p, off the bullet previously to permission being given by the cams S, U, for the spring S¹, to throw it out of the way 95 of the dies H, H, and punch. 100

V, is the knock-off lever for knocking the finished bullets off the core, arranged on a fulcrum y, below the table A, and having one extremity bent upward and protruding through a small hole in the table close to the side of the core I. This lever is struck once in every revolution of the shaft E, by a wiper W, on the fly wheel L, and by that means the extremity protruding through the 110 115 120 125 130

table is caused to rise suddenly and strike the lower edge of the bullet on the core, and knock it off, and tip it over on the opposite side of the core so that it falls through a 5 hole z , in the table into a suitable receptacle. To prevent the bruising of the bullet the knock off lever should be tipped with cloth, leather or some other soft substance, and the receptacle into which the bullets fall should 10 be kept well supplied with saw dust, bran or other soft granulated or foliated substance.

Having described the construction of the machine and the individual operations of the several parts I will in conclusion briefly 15 describe the process of forming and finishing the bullets as performed by it.

The bar of lead, represented in red outline in Fig. 3, having been fed by the feed rollers over the stationary die G, the punch 20 F, instantly descends and cutting a blank from the bar, drives it through the die G, and between the dies H, H, which close during the operation of cutting the blank. The continued descent of the punch within the 25 closed dies H, H, drives the lead over the core I, and causes the cavity or die i , within its own face to be filled up by the great pressure thus given to the lead, and this brings the bullet to the condition represented 30 in Figs. 4 and 8. Before the entry of the punch between the dies H, H, the band j , was shifted on the loose pulley h^1 of the core shaft, to leave the core stationary during the pressing operation; but as the dies 35 H, H, open and the punch rises the band is shifted on to the fast pulley h , and the revolution of the core with the bullet upon it, at a very high speed, commences, and the female center p , and cutter Q, advance, the 40 center moving forward at once and rapidly to a position directly over the bullet and then suddenly dropping on its tip, and the cutter moving forward rapidly to a position close to the bullet and then more slowly to 45 prevent too deep a cut being taken in the rapidly revolving bullet. The cutter after taking off the shoulder n , cutting the grooves v , v , and otherwise finishing the exterior of the bullet, is suddenly thrown back 50 to the position shown in bold outline in Fig. 4*, and at the same instant the female cen-

ter is raised from the tip of the bullet and thrown back to a position near the cutter. The retreat of the cutter and female center is followed by the rise of the knock off lever 55 which throws the finished bullet off the core and out of the machine and by the time this has been accomplished, the punch is again descending to cut another blank from the bar of lead which has been fed a proper distance over the die G, during the turning operation.

I do not confine myself to the use of a single core, as a series of cores may be arranged on a revolving or reciprocating plate 65 operated to carry them alternately, first into positions to combine with the dies and afterward into proper positions relatively to a cutter or cutters to turn the bullets. Nor do I confine myself to the use of a core of any 70 particular form nor to the manufacture of any particular form of bullet, nor to the use of any particular contrivances for giving motion to the several parts of the machine. But

What I claim as my invention and desire to secure by Letters Patent, is—

1. The employment in combination with a punch and set of dies, or their equivalent, for pressing blanks or pieces of lead into a 80 form approximating more or less to the desired form for hollow bullets, of a revolving core serving firstly to produce the cavities in the bullets and secondly as a mandrel to revolve them for the purpose of finishing 85 their exteriors by turning them, substantially as herein specified.

2. The employment in combination with the revolving core of a turning cutter operating automatically, substantially as herein 90 specified.

3. The employment in combination with the revolving core and turning cutter of a female center operating substantially as described, for the purpose of securing the bullets on the core during the turning operation, and liberating them after such operation.

RICHARD GORNALL.
